VISE

Samuel Thomas Nash, Woden Works, Wednesbury, England, assignor to The Steel Nut & Joseph Hampton Limited, Wednesbury, England

Application September 12, 1936, Serial No. 100,398
In Great Britain September 28, 1935

3 Claims. (Cl. 81—33)

This invention has reference to improvements relating to vises and is concerned particularly with vises of the kind in which a quick action of the movable jaw may be obtained by moving the screw out of engagement with the co-operating nut.

The present invention has for its object the provision of an improved vise having a quick action of the kind aforesaid and utilizing movable eccentric bearings for the screw which is simple in construction, efficient in operation and which incorporates a positive actuation of the eccentric bearings in which the screw is mounted.

The invention consists of an improved vise of the kind hereinbefore referred to wherein the screw is provided with means which is caused to engage positively with complementary means carried by a movable eccentric bearing for the screw to cause the eccentric to move the screw out of engagement with the nut when the screw is rotated in a counter direction to that employed for moving the jaws of the vise together.

The invention further resides in the details of construction of the improved vise to be described hereinafter.

A convenient embodiment of the invention will now be described with reference to the accompanying sheet of drawings in which similar reference numerals indicate similar parts in the different views.

Figure 1 is a longitudinal part sectional elevation of a vise constructed in accordance with this invention showing the nut and screw in engagement.

Figure 2 is a part sectional end elevation on line 2—2 of Figure 1.

Figure 3 is a longitudinal part sectional elevation similar to Figure 1, but showing the nut and screw out of engagement.

Figure 4 is a part sectional end elevation on line 4—4 of Figure 3, and

Figure 5 is a part sectional end elevation on line 5—5 of Figure 3, with parts broken away for clearness of illustration.

According to the illustrated embodiment of the invention the movable jaw 6 is formed integral with a box slide 6^a which is slidably mounted in a horizontal direction within the guide bracket 7 formed integral with the base 7^a. In both ends of the box slide there is housed a rotatable eccentric 8, the said eccentric being interconnected by a flat bar 9. Each eccentric 8 is provided with a bearing aperture in which is rotatably mounted the plain end sections 10^a of the screw 10, the buttress threads whereof co-operate with the

threads of a half-nut block 11 carried in the base 7^a by means of the integral shank 11^a and secured by the nut 12, the shank 11^a passing through a circular aperture 13^a in the plate 13, the plate 13 being fixed in a recess on the underside of the base 7^a by means of screws 13^b. The forward end of the screw spindle projects from the movable jaw 6 and has fixed thereon a boss 14 provided with a through aperture for the tommy-bar 15. The boss 14 is provided with a spring pressed 10 axially slid able plunger 16 which is adapted to co-operate with one or other of a pair of oppositely disposed ratchet teeth 8^a, 8^b formed in the outer face of the forward eccentric 8 mounted in the movable jaw 6. This forward eccentric carries a projecting pin 8^c which co-operates with a shoulder 6^b formed in the movable jaw 6 for limiting the counter-turning movement of the screw 10.

The operation of the vise is as follows:—

When the screw 10 is rotated in the direction to close the vise, for example, clockwise viewed from the forward end of the vise, the tendency is to rotate the eccentrics in the same direction as the screw, the thread of the screw 10 being in engagement with the thread of the half-nut block 11 as seen in Figures 1 and 2, thus enabling the jaws of the vise to close by the ordinary turning operation of the tommy-bar 15. Rotation of the screw 10 in this direction is permitted since the spring pressed plunger 16 rides over the ratchet teeth 8^a, 8^b formed in the forward eccentric 8 mounted in the movable jaw 6. The bar 9 connecting the eccentrics 8 is in the closing operation in the position seen in Figures 1 and 2 of the drawings, that is, the one edge of the bar is in contact with the top face of the one side of the half-nut block 11 as seen clearly in Figure 2, this bar 9 in addition to forming the means of connection between the two eccentrics 8 may also form a limiting stop for the motion of the eccentrics more particularly in the closing operation of the vise as seen in Figure 2. When the reverse motion of the vise first takes place this bar 9 is moved over the top of the screw 10 until the other edge of the bar abuts against the opposite top or side face of the half-nut block 11 as seen clearly in Figure 4.

When it is desired to obtain a quick action of the movable jaw 6 the screw 10 is rotated a half-turn in a counter clockwise direction by means of 50 the tommy-bar 15. This counter clockwise rotation causes the spring pressed plunger 16 carried by the boss 14 to engage with one or other of the ratchet teeth 8^a or 8^b formed in the forward eccentric 8 and thus to rotate the eccentrics 55

- until the stop pin 8^c carried by the forward eccentric comes into contact with the shoulder 6^b formed on the movable jaw 6 (see Figure 5). This counter clockwise motion through the pair of eccentrics lifts the thread of the screw 10 out of engagement with the thread of the half-nut block 11 so that complete freedom of the screw 10 obtains, and the vise jaw 6 can be freely moved longitudinally in either direction as required. In so disconnecting the thread of the screw 10 from the thread of the half-nut block 11 , the half-nut block is moved laterally in the base 7^a to the position seen in Figure 4, which motion is permitted by the clearance obtaining between the shank 11^a and the aperture 13^a in the plate 13 . This motion of the half-nut block 11 admits of a ready engagement and disengagement of the thread of the screw with or from the thread of the half-nut block.
- 20 By the invention as herein described a quick action vise is obtained which dispenses with the use of the usual lifting or release triggers or independent members for the disengaging operation.
- 25 What I claim is:—
1. A quick action vise comprising a fixed part, a movable part, a screw carried by the movable part, a half nut complementary to the screw, carried by the fixed part, eccentric bearing means 30 for the screw turnably mounted in the movable part, a projecting means turnable with the screw, and a complementary recessing of the eccentric bearing for engagement by the said projecting means said engagement resulting in the positive 35 turning of the eccentric bearing means so as to lift the screw out of engagement with the nut when the screw is rotated in a counter direction to that employed for moving the jaws together.

2. A quick action vise comprising a fixed part, a movable part, an eccentric bearing turnably mounted in opposed portions of the movable part, a screw rotatably mounted within the eccentric bearings, a half nut complementary to said screw and carried by a fixed part, means interconnecting the two eccentric bearings, a plunger carried by the screw, a ratchet tooth carried by an eccentric bearing and adapted to receive the projecting portion of the said plunger whereby when the screw is rotated in a counter direction to that employed for moving the jaws together the eccentric bearings are positively turned so as to lift the screw out of engagement with the nut to admit of a quick movement of the movable part.

3. A quick action vise comprising a fixed part, a movable part, an eccentric bearing means turnably mounted in the movable part, a screw rotatably mounted within the eccentric bearing means, a half nut complementary to the screw and carried by the fixed part, a spring pressed plunger carried by the screw and having a portion thereof which projects therefrom, a pair of oppositely disposed ratchet teeth formed in the eccentric bearing and adapted to receive a projecting part of the plunger whereby when the screw is rotated in a counter direction to that employed for moving the jaws together the said bearing means is turned positively by the engagement of the projecting portion of the plunger with one of the ratchet teeth and means for limiting the degree of movement permitted to the eccentric bearing means.

SAMUEL THOMAS NASH.
